FIG. 4.

FIG. 5.

UNITED STATES PATENT OFFICE.

FREDERICK E. KREATZ, OF ST. CLOUD, MINNESOTA.

PLUMB-LEVEL.

SPECIFICATION forming part of Letters Patent No. 765,847, dated July 26, 1904.

Application filed June 18, 1904. Serial No. 212,836. (No model.)

To all whom it may concern:

Be it known that I, FREDERICK E. KREATZ, a citizen of the United States, residing at St. Cloud, in the county of Stearns and State of Minnesota, have invented certain new and useful Improvements in Plumb-Levels, of which the following is a specification.

This invention relates to improvements in leveling instruments having weighted pointers for plumb-levels; and its object is to provide a simple, inexpensive, and durable device of this character. I attain these objects by the construction illustrated in the accompanying drawings, in which—

15 Figure 1 is a face view of the instrument, secured into an opening in a leveling-board, a portion of which is in section to show its retaining device. Fig. 2 is a transverse section of the instrument on line 2 2 of Fig. 1. 20 Fig. 3 is a perspective view of a ring used to separate the indicator-plate from its glass cover and form a chamber for the indicator-needle. Fig. 4 is a perspective view of a springy wire used to retain the glass cover 25 secured to the casing of the instrument. Fig. 5 is a modification of the leveling-board with the instrument attached thereto.

In said drawings, A represents a portion of the leveling-board, and B the metal casing 30 containing the operating parts of the device. Said casing is a cup-like cylinder having the bottom b, integral with the sides b². Said sides are thicker toward the bottom and are provided in the interior with an annular shoulder 35 c about half-way of their depth to receive and support the indicator-plate d, which plate constitutes a partition between the inner and the outer chamber. Centrally of the inner chamber there is a shaft e, one end of which is received in a bearing f, formed in the bottom b of the casing or within a boss projecting inwardly from said bottom. The opposite end of the shaft e is made to pass loosely through the plate d and has rigidly secured to said 40 45 end the indicator-needle g. To the shaft e is also secured a substantially triangular weight or arm h, which has substantially the whole of its weight on one side of the shaft e and its

center of gravity on a line parallel with the axis of the needle g. To provide a cylindrical chamber for said needle, a thin ring i of suitable width is provided, one edge of which rests against the face of the plate d. Upon the opposite edge of said ring is placed the glass cover k, which is retained in contact 50 with the ring i and locked in position by a spring-wire ring l, which is sprung into a groove m, formed in the interior of the sides b² of the cup-like casing B.

The casing is retained secured to the leveling-board A by means of a screw n, the end of which impinges against said casing. Said screw is in engagement with a screw-tapped nipple p, which is driven tight or otherwise secured into the edge of the leveling-board A. 65 The screw n may also be made to engage directly with the leveling-board.

In Fig. 5 the leveling device A² is intended to be made of metal, one edge of which has two short arms q, which partially embrace 70 the casing B, said arms having screws n² passing therethrough.

Having fully described my invention, I claim—

A plumb-level consisting of a leveling-board, a cup-like casing having a bottom and sides integral therewith, said sides being thicker next to the bottom, having a shoulder c about half-way thereof, an indicator-plate d bearing on said shoulder, a ring i bearing on 75 the plate d, a glass cover, and a spring-wire ring l, the sides of the casing having an annular groove m to receive said spring-ring, with the shaft e of the instrument having a weighted arm h, and an indicator-needle g 80 secured to one end of said shaft, said needle being adapted to rotate within the device in a chamber having for its periphery the ring i, substantially as described.

In testimony whereof I affix my signature in 85 presence of two witnesses.

FREDERICK E. KREATZ.

Witnesses:

ANDREW C. ROBERTSON,
ALFRED JOHNSON.
